(57) **CLAIM**

The ornamental design for a firearm grip, as shown and described.

DESCRIPTION

FIG. 1 is a top, left, front perspective view of a first embodiment of a firearm grip showing our new design;

FIG. 2 is a front elevation view of the firearm grip of FIG. 1; FIG. 3 is a rear elevation view of the firearm grip of FIG. 1; FIG. 4 is a right side elevation view of the firearm grip of FIG. 1;

FIG. 5 is a left side elevation view of the firearm grip of FIG. 1;

FIG. 6 is a top plan view of the firearm grip of FIG. 1; FIG. 7 is a bottom plan view of the firearm grip of FIG. 1; FIG. 8 is a bottom, left front perspective view of the firearm grip of FIG. 1;

FIG. 9 is a top, left, front perspective view of a second embodiment of a firearm grip showing our new design;

FIG. 10 is a front elevation view of the firearm grip of FIG. 9; FIG. 11 is a rear elevation view of the firearm grip of FIG. 9; FIG. 12 is a right side elevation view of the firearm grip of FIG. 9;

FIG. 13 is a left side elevation view of the firearm grip of FIG. 9;

FIG. 14 is a top plan view of the firearm grip of FIG. 9;

FIG. 15 is a bottom plan view of the firearm grip of FIG. 9; and,

FIG. 16 is a bottom, left front perspective view of the firearm grip of FIG. 9.

The stippling in FIGS. 1-8 shows a contrast in appearance with no particular color, material, texture or other feature being claimed thereby.

FIGS. 9-16 show the identical design of FIGS. 1-8 without stippling to further clarify the design and to illustrate an alternate embodiment.

The broken lines immediately adjacent solid lines represent the bounds of the claimed design while all other broken lines are included for the purpose of illustrating environment and unclaimed features and form not part of the claimed design.
